UNITED STATES PATENT OFFICE.

NATHANIEL L. BRADLEY, OF WEST MERIDEN, CONNECTICUT, ASSIGNOR TO
BRADLEY & HUBBARD, OF SAME PLACE.

DESIGN FOR LAMP-PEDESTAL.

Specification forming part of Design No. 7,158, dated February 10, 1874; application filed September 16, 1873.
[Term of Patent 7 years.]

A.

To all whom it may concern:

Be it known that I, NATHANIEL L. BRADLEY, of West Meriden, in the county of New Haven and State of Connecticut, have invented a new Design for Lamp-Pedestal; and I do hereby declare the following, when taken in connection with the accompanying drawing, to be a full, clear, and exact description of the same, and which said drawing constitutes part of this specification, and represents a front view.

The invention relates to a design for the pedestal of a lamp; and it consists in a hand, the wrist resting upon the base, and the fingers supporting the bowl of the lamp, as shown in the accompanying illustration, and as herein-after described.

A is the base; B, the lamp-bowl, either of

which may be of any desired form, the form of these parts being no part of the design. The lower portion of the pedestal or support of the lamp is a hand, the wrist resting upon the base and in nearly a vertical position, the fingers grasping the upper portion of the pedestal, giving to the lamp the appearance of being held in the hand, substantially as shown in the accompanying illustration.

I claim as my invention—

The design for lamp-pedestal, substantially as shown and described, consisting of the hand resting upon the base and supporting the lamp.

N. L. BRADLEY.
